COMBINED DIAL AND HANDS FOR A TIMEPIECE

Robert C. Burroughs, 11208 Evans Trail, Apt. 102,
Beltsville, Md. 20705

Filed May 4, 1971, Ser. No. 140,308

Term of patent 14 years

Int. Cl. D10—07

U.S. Cl. D42—1

FIG. 1

FIG. 2

FIG. 3

FIG. 1 is a top plan view of a combined dial and hands for a timepiece showing my new design.

FIG. 2 is a right side elevational view thereof.

FIG. 3 is a top plan view of the second hand.

I claim:

The ornamental design for a combined dial and hands for a timepiece, substantially as shown and described.
